(57) **CLAIM**

The ornamental design for an inkjet printer, as shown and described.

DESCRIPTION

FIG. 1 is a perspective view of the top, front and right side of an inkjet printer showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a view similar to FIG. 1 with paper guiding sheets in the extended position.

1 Claim, 4 Drawing Sheets
